CLAIM

The ornamental design for a hip thrust cushion as shown.

DESCRIPTION

FIG. 1 is a perspective view of a first embodiment of a hip thrust cushion showing our new design.

FIG. 2 is a top view thereof.

FIG. 3 is a front view thereof. The rear view is the same as the front view.

FIG. 4 is a bottom view thereof.

FIG. 5 is a right side view thereof. The left side view is the same as the right side view.

FIG. 6 is a perspective view of a second embodiment of a hip thrust cushion showing our new design.

FIG. 7 is a top view thereof.

FIG. 8 is a front view thereof.

FIG. 9 is a rear view thereof.

FIG. 10 is a bottom view thereof; and,

FIG. 11 is a right side view thereof. The left side view is a mirror image of the right side view.

1 Claim, 8 Drawing Sheets
